[57] CLAIM

The ornamental design for a battery and tool box for a truck, as shown and described.

DESCRIPTION

FIG. 1 is a perspective view of a battery and tool box for a truck showing a first embodiment of our new design;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a bottom view thereof;

FIG. 8 is a perspective view of a battery and tool box for a truck showing a second embodiment of our new design;

FIG. 9 is a front view of FIG. 8;

FIG. 10 is a right side view of FIG. 8;

FIG. 11 is a back view of FIG. 8;

FIG. 12 is a left side view of FIG. 8;

FIG. 13 is a top view of FIG. 8; and,

FIG. 14 is a bottom view of FIG. 8.

The latching hardware shown in broken lines is for illustrative purposes only and forms no part of the claimed design.
